UNITED STATES PATENT OFFICE.

RICHARD MUNDLOS, OF MAGDEBURG, GERMANY, ASSIGNOR TO THE FIRM OF H. MUNDLOS & CO., OF MAGDEBURG, GERMANY.

THREAD-CUTTING DEVICE FOR BUTTONHOLE-SEWING MACHINES.

1,218,107.

Specification of Letters Patent. Patented Mar. 6, 1917.

Application filed May 20, 1915. Serial No. 29,290.

To all whom it may concern:

Be it known that I, RICHARD MUNDLOS, a subject of the King of Prussia, and residing at Magdeburg-N., in the Kingdom of Prussia and German Empire, have invented certain new and useful Improvements in Thread-Cutting Devices for Buttonhole-Sewing Machines, of which the following is a specification.

10 My invention relates to a thread cutting device or mechanism for sewing machines and particularly of a kind adapted for use in button hole sewing machines.

15 The object of my invention is to provide a thread cutting mechanism by which the two threads in the machine, that is the upper thread and the lower thread, are simultaneously cut when the machine is at rest.

20 My invention is shown in the accompanying drawings wherein:

Figure 1 is a side view of the parts of a button hole sewing machine embodying the invention.

Fig. 2 is a plan of the same.

25 Fig. 3 is a partly sectional view of a part of the mechanism for cutting the upper thread and the lower thread on a larger scale showing the parts in the position during the cutting operation.

30 Fig. 4 is a view of the mechanism for cutting the lower thread on a larger scale.

The devices for cutting off the upper thread and the lower thread or the upper cutting device and the lower cutting device 35 are held in operative interdependence by the presser member so that the two devices simultaneously begin the cutting operation. The presser member is formed at its fore-end so as to act like the so-called presser foot and carries at this end the detachable blade or cutter 2 for cutting the upper thread. Said cutter 2 is of angular shape, and can be easily detached from its carrier, *e. g.* for grinding purposes, and again attached thereto without the necessity of removing any other parts from their operative positions. The presser member comprises two levers or parts 1^a and 1^b mounted on hinges 3 and 4 respectively, the part 1^b 40 being free to turn on its hinge 4 to a certain extent independently of the part 1^a, the two parts being turned together about the hinge 3 for the purpose of lifting the presser foot 45 from the sewing plate 12 or the work 50

(fabric or the like) thereon. This turning or oscillating movement of the presser member is effected by means of a treadle (not shown) and a member (not shown) such as a rod or chain connecting the treadle with the part 1^b as is well understood by those skilled in the art. In actuating the treadle the part 1^b is first turned downward alone about 4, thereby acting upon an angle shaped plate 6 adjustably mounted on a slotted lever 5 having its fulcrum at 7 and being directly connected with the actuating rod 8 of the lower cutting device which is controlled by a spring 11, by means of a pin 10 engaging the slot 9 of the lever 5. The said rod 8 is at the other end, connected 60 with the arm 14^a of a lever 14 having its fulcrum at 13 below the sewing plate 12 and engaging, with its forked arm 14^b, the pin 18 of the lever 19 operating the blade or cutter 16 for cutting the lower thread. The 65 cutter 16 is connected with the arm 17 of the lever 19 having its fulcrum at 15. The lever arm 17 serves the special purpose of pulling off the lower thread and the lever 70 14 is controlled by a spring 20. By the 75 action of the part 1^b of the presser member on the plate 6 of the slotted lever 5 the latter is turned about its fulcrum 7 so that the rod 8 engaging the slot 9 of the lever 5 by means of its pin 10, is longitudinally moved forward against the action of its spring 11 and thereby the lever 14, the cutter 16 and the thread pulling arm 17 are simultaneously actuated. In turning the lever 5 downward 80 from its normal position the plate 6 acts 85 upon a lever 22 fulcrumed at 21 and controlled by a spring 23, so that the lever 22 90 rotates against the action of its spring 23 which holds the lever 22 at all times in contact with the plate 6 and also causes the 95 lever 22 to return to its normal position when the lever 5 reassumes its normal position. In starting the sewing machine the presser member moves forward, as usually in machines of this kind, so that the lever 22 100 at the time will not be in contact with the rod 24, engaging only the adjustable plate 6 of the lever 5. At the backward movement of the presser member the said rod 105 bears against the fore-arm of the lever 22 and is held under pressure by the action of its spring 26; thus the rod 24 is moved forward with relation to the presser member

1^a, 1^b whereby the thread pulling member 29 mounted on a vertical rod 28 so as to rotate thereon, is turned by the lever 27 into the proper actuating position. As soon as the lever 22 moves down, the rod 24 is released and thereby the thread pulling member 29 on the shaft or rod 28 is turned under the action of the rod 24 connected therewith by the arm or lever 27, so as to pass by the blade or cutter 2 for the upper thread and cause the latter to be cut off.

The angular end 25 of the lever 22 forms a separate part and can be adjusted with relation to the lever by means of a screw and nut 31 in a longitudinal slot 30 of the lever 25. In order to not actuate the cutting off before the machine is stopped a cam lever 33 is connected with the disengaging member 32 of the machine drive, said lever 33 assuming, as long as the machine is working, a position below the angular plate 6 of the lever 5 so as to lock the latter and the presser member 1^a 1^b and thus prevent the cutting devices for the upper and the lower thread from operating. The cam lever 33 is so shaped or fashioned as to be adapted to prevent the machine from being engaged or coupled and started so long as the presser member 1^a 1^b is open or lifted and at the same time to assist in the lifting of the slotted lever 5. The said cam lever 33 has its fulcrum at 34 and is connected with the disengaging member 32 of the machine by the arm 35 and the link 36, lever 37 and link 38. The lever 37 is fulcrumed at 39. As soon as the machine is stopped by means of the disengaging mechanism, the cam lever 33 releases the lever 5 and the angular piece 6 attached thereto so that the presser member 1^a 1^b is free to turn or oscillate and the thread cutting devices can be actuated simultaneously by the movement of the slotted lever 5, 6 and the locking lever 22 in the manner aforescribed.

45 As soon as the part 1^b of the presser member is actuated to operate the levers 5 and 22 and has finished part of its way a pin 40 adjustably mounted at the lower face of the said part 1^b begins to act on the back end of the part 1^a of the presser member to turn said part 1^a about its pivot 3 so that the fore-end of the part 1^a is lifted from the machine plate or the fabric thereon. On releasing the treadle and the part 1^b connected therewith the presser member is returned to its initial or normal position by means of springs 41 and 42, the former being mounted between the superposed ends of the two parts 1^a 1^b of the presser member, the latter acting on the fore-end of the part 1^a. At the same time the cam lever 5 is returned to its initial position by means of a link or chain 43 connecting said lever with the part 1^b of the presser member.

60 65 The rod 24 is moved forward owing to the

backward movement of the presser member whereby the thread pulling member 29 rotatably mounted on the vertical rod 28, is turned by the lever 27 into the proper operating position. The thread pulling member 29 is provided on its upper face with ribs or teeth which act to hold the thread and draw same back again so that the thread never can be caught.

As regards the operation of the cutter 16 it is to be noted, that the lower thread comes from the bobbin in the bobbin case or box and passes through the vertical hole in the stitching-plate to the work. As the cutting device is being operated the lever arm 17 pulls off the thread from the bobbin, but said lever arm 27 never can pull the thread out of the range of movement of the cutter 16, since the thread passes through the hole in the stitching plate and the cutter moves close by said hole.

What I claim is:

1. In a button-hole sewing machine, a presser member fulcrumed to the machine-plate, a device for cutting off the upper thread, a device for cutting off the lower thread, a rod, 24, adapted to actuate the former, and a rod, 8, adapted to actuate the latter, a lever, 5, in operative connection with the said rod, 8, and in engagement with the presser member, and a lever, 22, in engagement with the other rod, 24, and with the other lever, 5, to be moved simultaneously therewith.

2. In a button-hole sewing machine, a presser member fulcrumed to the machine-plate, a device for cutting off the upper thread, a device for cutting off the lower thread, a rod, 24, adapted to actuate the former and a rod, 8, adapted to actuate the latter, a lever, 5, in operative connection with the said rod, 8, and in engagement with the presser member, a lever 22 in engagement with the rod, 24, and the lever, 5, and an adjustable angular end piece, 25, on said lever, 22, adapted to bear against the cutter actuating rod, 24.

3. In a button-hole sewing machine, a presser member fulcrumed to the machine-plate, a device for cutting off the upper thread, a device for cutting off the lower thread, a rod, 24, adapted to actuate the former and a rod, 8, adapted to actuate the latter, a lever, 5, in operative connection with the said rod, 8, and in engagement with the presser member, a lever, 22, a cam lever, 33, a member, 32, for disengaging the machine drive, and intermediate means connecting said cam lever with the said member, 32, all the parts constructed and arranged so that the aforesaid levers, 5 and 22, are locked when the machine drive is engaged.

4. In a button-hole sewing machine, a presser member fulcrumed to the machine-

plate, a device for cutting off the upper thread, a device for cutting off the lower thread, a rod, 24, adapted to actuate the former and a rod, 8, adapted to actuate the latter, a lever, 5, in operative connection with the said rod, 8, and in engagement with the presser member, a lever, 22, a cam lever, 33, so shaped or profiled as to prevent the machine from being engaged or coupled to start when the presser member is lifted or open, and to assist in lifting the lever 5, a member 32, for disengaging the machine drive, and intermediate means connecting said cam lever with the said member 32.

5. In a button-hole sewing machine, a presser member fulcrumed to the machine plate, a device for cutting off the upper thread, a device for cutting off the lower thread, a rod, 24, adapted to actuate the former, and a rod, 8, adapted to actuate the latter, a lever, 5, in operative connection with the said rod, 8, and in engagement with the presser member comprising two superposed parts or levers, the one, 1^a, being fulcrumed to the machine plate, the other, 1^b, being fulcrumed on the former, so as to act, when actuated, first on the said lever, 5, alone, and thereafter on the part, 30 1^a, for the purpose of operating same.

6. In a button-hole sewing machine, a presser member fulcrumed to the machine plate, a device for cutting off the upper thread, a device for cutting off the lower thread, a rod, 24, adapted to actuate the former, and a rod, 8, adapted to actuate the latter, a lever, 5, in operative connection with the said rod, 8, and in engagement with the presser member comprising two superposed parts or levers, 1^a, 1^b, and two springs 42, 41, acting on said levers

respectively to return same to their normal position.

7. In a button-hole sewing machine, a presser member fulcrumed to the machine-plate, a blade or cutter, 2, for cutting off the upper thread detachably fixed to the forward end of the presser member, a thread pulling member, 29, movably connected therewith and provided with ribs or teeth acting to hold the thread and prevent same from being retained, a rod, 24, adapted to actuate both the said cutter and the said member, 29, a device for cutting off the lower thread, a rod, 8, adapted to actuate the latter, a lever, 5, in operative connection with the said rod, 8, and in engagement with the presser member, and a lever, 22, in engagement with the other rod, 24, and with the other lever, 5, to be moved 60 simultaneously therewith.

8. In a button-hole sewing machine, a presser member fulcrumed to the machine-plate, a device for cutting off the upper thread, an actuating rod, 24, a blade or cutter, 16, for cutting off the lower thread, a thread pulling member, 17, both the latter and the said cutter being connected to rotate about the same pivot 15, an actuating rod, 8, a lever, 5, in operative connection 70 with the said rod, 8, and in engagement with the presser member, and a lever, 22, in engagement with the other rod, 24, and with the other lever, 5, to be moved simultaneously therewith.

In testimony whereof I have affixed my signature in presence of two witnesses.

RICHARD MUNDLOS.
